UNITED STATES PATENT OFFICE.

OTIS A. MYGATT, OF NEW YORK, N. Y.

DESIGN FOR AN ARTIFICIAL-LIGHT REFLECTOR.

No. 38,543.

Specification for Design.

Patented April 30, 1907.

Application filed July 14, 1905. Serial No. 269,730. Term of patent 14 years.

To all whom it may concern:

Be it known that I, OTIS A. MYGATT, a citizen of the United States, residing at New York, in the county of New York and State of New York, have invented a certain new, original, and ornamental Design for Prismatic-Glass Reflectors, of which the following is a specification, reference being had therein to the accompanying drawing, forming part thereof.

Figure 1 is a side elevation of a reflector embodying my design. Fig. 2 is a top plan of the reflector.

I claim as my invention:

The ornamental design for an artificial light reflector, as shown.

OTIS A. MYGATT.
